UNITED STATES PATENT OFFICE.

WILBER L. ROOT, OF CINCINNATI, OHIO.

APPARATUS FOR ATOMIZATION.

No. 856,301.

Specification of Letters Patent.

Patented June 11, 1907.

Application filed January 22, 1900. Serial No. 2,300.

To all whom it may concern:

Be it known that I, WILBER L. ROOT, a citizen of the United States, and a resident of the city of Cincinnati, in the county of Hamilton and State of Ohio, have invented 5 certain new and useful Improvements in Apparatus for Atomization, of which the following is a specification.

This invention relates, in general, to improvements in medical apparatus for coarse atomization and also for fine atomization, or what is commercially known as a combined or multiple nebulizer.

The several features of my invention and 15 the various advantages resulting from their use conjointly or otherwise will be apparent from the following description and claims.

The main objects of this invention are,—

First:—To provide an improved apparatus 20 in which is combined in a small and compact form a durable, simple and complete device which can be used in direct connection with a supply of compressed air for all practical uses of coarse and fine atomization (as for

25 instance, in sprays, douches, vaporizers and inhalers generally). Secondly:—To provide convertible air connections, so that the apparatus can be used in the different positions it is expected to occupy, when in actual and 30 practical use by physicians. Thirdly:—To provide an air filter chamber, to arrest the moisture and the many impurities present in compressed air, which interfere with the perfect operation of the valves and spray

35 tubes, and deteriorate the medicine. Fourth:—To provide in the apparatus an automatic air regulator, so that the air which enters the atomizing tubes shall enter at the desired pressure for which it has been set 40 regardless of the varying higher pressure from the source of supply. Fifth:—To provide constructions, in which all of the parts are accessible and separable, also in which the passages for the conduction of liquid are

45 perfectly straight, thus enabling them to be easily cleaned and kept in order, although the liquids employed may be any and all balsamic solutions, heavy oils, and the like. Sixthly:—To provide devices adapted for 50 the different methods of treatment, viz: for using coarse atomization for cleansing, medicating and for using the fine atomization by inhalation, dilation, resistance in exhalation, and vibrating massage effect. Seventh:—

55 To provide an improved combined atomizer having two or more medicines, arranged so

that any one of these medicines can be used 60 separately or that one or more can be quickly and conveniently mixed or diluted with one or more of the others, in the desired proportions. Eighth:—To provide air tight stop cocks over each bottle so as to prevent the evaporation of the medicines when not in use, to prevent back pressure of nebula vapor 65 into the bottles of medicine not needed, when one or more of the other bottles of medicine are in use. Ninthly:—To furnish a provision for blowing out of the tubes all of the nebula vapor remaining in the tubes after air has been shut off from the spray tubes. Tenthly:—To provide an attachment, of a 70 vibrating valve, that can be easily held in the hand close to the patient's face, where it is convenient and safe to use effectively with the thumb or electric battery sounding attachment. 75

Other subordinate objects attained by my invention will be apparent in the detailed description of my apparatus.

In the accompanying drawings making a 80 part of this application, and in which similar letters of reference indicate corresponding parts,—Figure 1, Sheet 1, is a front elevation of my apparatus. Fig. 2 is a side or end elevation of the same. Fig. 3 is an enlarged 85 (actual size) sectional view taken vertically through the central part of the apparatus in the plane of the dotted line 3, 3, of Fig. 1. Fig. 4 is a plan view of the main casing of the apparatus shown in Fig. 3. Fig. 5 is a horizontal 90 sectional view taken transversely through the main casing, in the plane of the dotted line 5, 5, of Fig. 3. Fig. 6 is an enlarged sectional view taken vertically through the upper part of one of the bottles and its 95 air and vapor connections, in the plane of the dotted line 6, 6, of Fig. 1. Fig. 7 is a view similar to Fig. 6, but showing the controlling valve in another position. Fig. 8 is a view similar to Figs. 6 and 7, but showing still another position of the valve. Fig. 9, Sheet 3, is an enlarged sectional view taken axially through the lower end of one of the atomizing tubes, the valve being shown in elevation. Fig. 10 is a sectional view taken transversely through the atomizing tube in the plane of the line 12, 12, of Fig. 11, that face of the section being shown which faces upward in Fig. 11. Fig. 11 is a sectional view showing the construction of the base plate on 105 which the apparatus is held. Fig. 12 is a sectional view showing a modified arrange- 110

ment of the base plate for supporting the apparatus in position on wall or vertical support. Fig. 13 is an enlarged view showing the arrangement of the indexes of the controlling valve.

I will now proceed to describe my invention in detail.

The apparatus is suitably supported. In all preferred modes of support, the bottom of the bottles are kept out of contact with everything except the surrounding air. The preferred means of support will be hereinafter specified.

A indicates the chamber which receives the air under pressure from the conduit A²—the other end of this conduit is connected with the source of pressure. This air under pressure may be furnished by a suitable air pump. This chamber contains a filtering material or materials through which the compressed air must pass from conduit A² on its way to the rest of the apparatus. In the present illustrative instance, the materials consist of layers B of absorbent cotton separated by layers of gauze B². In connection with this device, I provide an air pressure gage C of any well known form. In connection with this gage, I provide a construction whereby I can regulate the pressure of incoming air and deliver this air at a given pressure to the rest of the apparatus. In a suitable portion of the shell of the chamber A, I make an aperture C², and in the latter I locate a valve C³. I connect the latter by a shank to a diaphragm C⁴, the latter being in contact with a spring C⁵. The diaphragm is located on bearing C⁶ and held down by a gasket C⁷, in turn secured by a sleeve C⁸ screwed into the extension of the chamber A as shown. Into this sleeve is screwed a nut C⁹, whose interior receives the upper portion of the spring C⁵. The pressure of spring C⁵ upon the diaphragm is regulated by the vertical adjustment of the nut C⁹. Through the nut C⁹ is a passage C¹⁰, for keeping the air within the nut and space above the diaphragm at the same pressure as the outer atmosphere. The conduit C¹⁰ from aperture or valve seat C², reaches the diaphragm C⁴, and also the pressure gage C, and then extends so as to connect substantially as shown with the rest of the apparatus. In consequence, I am enabled in connection with the reading of the gage to regulate the degree of air pressure at which the diaphragm C⁴ shall operate to close the valve C³. The mode in which these parts operate is as follows. The spring C⁵ will, when no pressure is exerted on the diaphragm, keep the diaphragm depressed and the valve depressed and open. I admit air under pressure to the chamber A, and this passes through the open valve and presses against the diaphragm and the pressure gage. I now adjust the nut so that the pressure of air against the diaphragm

shall overcome the resistance of the spring C⁵, at a time when the pressure gage indicates the pressure desired. Thereafter whenever the pressure of air in the conduit C¹⁰ exceeds in any degree the desired pressure, this pressure will press hard enough upon the diaphragm C⁴ to overcome the pressure of the spring C⁵, and raise this diaphragm C⁴, and seat the valve C³, thus gradually closing the latter and reducing the admission of air under pressure until the pressure of air in the conduit C¹⁰ and in the remainder of the apparatus above the stop cock has diminished to the amount at which the diaphragm is set for opening the valve. The spring will automatically allow the valve C³ to open and admit more air under pressure to the amount which by this adjustment the operator desires to use, and is indicated or recorded by the pressure gage. As the compressed air passes through the chamber A and the absorbent materials mentioned therein, it is purified and enters the remainder of the apparatus in a condition suitable for use in connection with the nasal passages, middle ear or the respiratory organs. This device enables the operator to reduce the pressure of the air escaping to any desired pressure and consequently the compressed air in a cylinder will last nearly twice as long; and by its use there is no waste of air and energy.

I locate in chamber A and in the space near the valve a perforated guard partition A³. The function of this partition is to prevent any of the absorbent material in chamber A from reaching and clogging the valve C³. The perforations allow the air passing through the chamber to freely pass to the valve C³. The conduit C¹⁰ from the source of compressed air by way of the chamber A duly connects through passage D², D³, with a discharge orifice D, and the passage of air to the latter is controlled by a suitable valve D⁴, preferably as shown, a conical valve, advanced and retracted by a screw thread of it, engaging a thread in the adjacent portion of chamber A, and rotated by a handle D⁵. To the discharge orifice D, rubber tubing D⁶ is attached for operating sprays, douches, etc., or for coarse atomization for cleaning and medicating purposes. A stuffing box C¹⁴ is present to keep the valve E² air tight.

The conduit C¹⁰ duly connects by way of conduit C¹² with a tube E extended substantially as shown and supported in a projection as C¹³ of the chamber A. The conduit C¹² which is simply an extension of the conduit C¹⁰ is preferably larger than that conduit, so as to be in a better condition to supply the tube E. The inlet to tube E is controlled by a valve E¹⁰, preferably of the conical form and advanced or retracted by the screw thread on the shank thereof engaging a thread on the extension of the chamber, the valve being operated by a thumb wheel or handle

⁵ ^E³. A stuffing box C¹⁵ is present to make the valve E¹⁰ air tight. Another tube F, preferably larger than tube E, extends parallel to the latter. The tube F at certain intervals, has extensions F², whose lower ends are each adapted to be connected at F⁴ to a vessel F³. A preferred mode of such connection is by a screw thread on the upper end of the vessel, engaging an interior screw on ¹⁰ an extended sleeve F⁵ of the extension F². From this tube F, there extends through the extension F² a passage F⁶, to the upper space within the vessel F³. The tube E is likewise connected with the vessels F³, by means of a ¹⁵ conduit E² extending to tube F and extending past the latter and then in a contracted form E³ to the upper end of a conduit E⁴, extending down into the vessel F³. The latter is preferably removable and to this end its ²⁰ upper portion is secured to the extension F² by means of a screw connection. The conduits E² and E³ and conduit F² are located in one piece, forged or cast, rather than composed of separate pieces soldered or ²⁵ otherwise united.

The conduit F⁶ and conduits E², E³ are controlled by suitable valvular means. I provide one valve shank G to control these conduits. I incline this shank at an angle ³⁰ substantially as shown to the conduit F⁶ and to the conduit E³. The shank is provided with a handle G² arranged for rotating the shank G relatively to the conduits. For the purpose of enabling the operator to adjust ³⁵ the valves relatively to the connections to be made, I provide on the outer end of the shank G² (see more particularly Fig. 13) three index pointers,—one marked "On," one marked "Off" and one marked "Air." A mark G³ on the extension F² is the place where the index is to point when performing the operation marked upon it. Thus when the index marked "On" is pointing to mark G³ (see Fig. 6), then the passage F⁷ through the ⁴⁰ shank alines with the conduit F⁶, and the passage E⁵ through the shank alines with the conduit E³. Then both of the conduits are open and the air from the tube E passes down through conduits E², E³, E⁴ and nebulizes the fluid of the bottle and then the nebulized vapor passes up through conduit F⁶ and through tube F to the tubing H, whereby it is delivered to the patient. When the ⁴⁵ index marked "Off" points to mark G³ (see Fig. 8), then both of the valves are shut off and no air can pass, and the medicines in the vessel beneath are closed air tight, not permitting evaporation or volatile parts escaping. When the index marked "Air" points ⁵⁰ to mark G³ (see Fig. 7), then both of the valves F⁷ and E⁵ are shut, but a passage E⁶ (preferably located in the peripheral portion of the shank) connects the conduit E² and upper part of conduit E³ with the upper portion of the passage F⁶. Thus passage of air

coming through tube E is circulated, and passes into tube F and thence into the discharge tubing without passing through the conduit E⁴ or through the vessel. It is to be noted that all of the metallic exit conduits ⁷⁰ are provided as shown, with the customary lining of hard rubber, to prevent corrosion. The valve shank is securely held in place, preferably by a spring E⁹ and nut E¹⁰. The object of thus causing the air to circulate, at ⁷⁵ will, through the tubes E and F and through the upper portion of conduit F⁶ is to cleanse these, so that little or no deposit from the nebulized vapor will form on the inner surface of the passage or of the discharge tubing ⁸⁰ H, and that these passages and the discharge tubing may be practically clean and in readiness for use with any other description of medicine which it is desired to employ.

The preferred and very advantageous construction of the lower portion of the conduit tube E⁴ and of parts supplied and combined therewith is as follows. The tube E⁴ extends down and its bottom is duly closed as shown. Around the lower portion of the tube is another tube J, there being a space between the sleeve and the tubes for the greater portion of the length of the sleeve. The upper end of tube J is in close contact with tube E⁴ and supported by means of the screw threaded ⁹⁰ valve hereinafter described. The walls of the tube E⁴ are outwardly reduced at J³ as shown, and thus enable an annular space J² to be present between the two tubes, without compelling the tube J to be of an outer diameter much larger, if any, than that of the tube E⁴. Through the side of the tube E⁴ is a narrow passage E⁷ inclined from within upward. Opposite the axial direction of the passage E⁷ is a larger passage or duct J⁴ ⁹⁵ through the tube J. The air under pressure passing down tube E⁴, passes rapidly in a slender stream through the passage E⁷, and thence through the passage J⁴. This operation creates a vacuum in the space J² and ¹⁰⁰ raises up the liquid into this space and projects it in atomized condition through passage J⁴ into the vessel F³ outside of the tube J, the coarse particles falling back into the bottom of the vessel and the finer or nebulized liquid passes up with the current caused by the jet of air escaping from passage and ¹⁰⁵ through the passages F⁶ and F and discharge tubing H to the patient. A screw valve E⁸ engaging a screw thread in the tube E⁴ has a seat in connection with the passage E⁷. By advancing or retracting the valve, the passage is closed or the size of it graduated as desired, according to the liquid state of the medicine delivered to the patient, and taking ¹¹⁰ into account the pressure of the air in tube E⁴. The shank of this valve not only screws through tube E⁴, but through tube J³ and thus supports the latter. To increase the ¹¹⁵ capacity of this device for nebulization, I ¹²⁰

employ as desired two or more such sets of passages E^7, J^3 , and valve E^8 . Thus in Fig. 9, I illustrate two such sets of passages and their valves.

5 Advantageous means for changing the support of the apparatus are shown: When the apparatus is supported on a standard S , as shown, this standard may be hollow and constitute the inlet conduit A^2 from the source 10 of compressed air as heretofore indicated. The standard in such event may be located upon a cylinder containing the compressed air.

Where the standard is solid, the compressed air may be admitted by way of the entrance T and a conduit T^6 shown in dotted lines in Fig. 2. But there are many occasions where it is desirable to support the apparatus from a side support; in such event, a 15 connection as T^2 is placed in the lower opening of the chamber A and the inlet tube T^6 is connected thereto. Then in the opening T is screwed the screw stopple T^3 , having on its center a ring T^4 . The latter aids in effectually closing the opening and in preventing the screw from going in too far. The screw 20 thread of the stopple on the outside of the ring receives a suitable bracket T^5 , which can be duly secured to the side support. 25 When desired, this stopple can be screwed directly into the side support instead of into the bracket. The bracket T^5 may be used as the foot or basal support of the vertical standard S , when the latter is present (see 30 Fig. 11), thereby avoiding a repetition of pieces.

In regard to the application of absorbent cotton as a useful factor in the process of my apparatus, I am aware that the material 40 known as sponge has been employed as a medium through which air has been passed, on its way to the medicating apparatus, and I do not claim the use of sponge, but I have found that sponge is a quite imperfect medium of absorption of moisture, etc., contained in the air; and that much of the air to be medicated will pass through it without being filtered. I employ absorbent cotton and gauze. The absorbent cotton is not 45 only free from impurities, but is also a very perfect absorbent of all moisture, and dust, etc., in the air. The air consequently will be very dry and pure. Being very dry, it is in condition to absorb the largest amount of 50 medicated vapor possible, in other words to be fully impregnated with the medicated vapors.

What I claim as new, and of my invention and desire to secure by Letters Patent, is:— 60 1. In an apparatus for inhalation having the air tube E and nebulized vapor tube F , an air chamber and layers alternate of absorbent cotton and gauze, and a conduit connected to the chamber for supplying air thereto, and an air exit conduit at another

part whereby the incoming air is compelled to pass through the absorbent material, and a perforated guard around said outlet for keeping the absorbent material from the exit tube, substantially as and for the purposes specified. 70

2. In an apparatus for inhalation, an air chamber containing absorbent material, an inlet conduit to said chamber, an outlet conduit provided with a valve seat, a valve, a diaphragm connected to said valve, and elastic means for keeping the valve open when allowed to do so, an adjusting device for changing the elastic pressure upon said valve, and a pressure gage, the air space for 80 operating the latter being also in contact with the diaphragm aforementioned, and in communication with the rest of the apparatus, substantially as and for the purposes specified. 85

3. In an apparatus for inhalation, an air chamber containing absorbent material, an inlet conduit to said chamber, an outlet conduit provided with a valve seat, a valve, a perforated guard between said valve and the 90 absorbent material, a diaphragm connected to said valve, and elastic means for keeping the valve open when allowed to do so, an adjusting device for changing the elastic pressure upon said valve, and a pressure gage, the air space for 95 operating the latter being also in contact with the diaphragm aforementioned, and in communication with the rest of the apparatus, substantially as and for the purposes specified. 100

4. In an apparatus for inhalation, the combination of the air chamber provided with the two inlet entrances, absorbent chamber, exit orifice located as shown and a supporting standard as S carrying the conduit 105 of air supply to the chamber A , substantially as and for the purposes specified.

5. In an inhalation apparatus, a vessel provided with an air inlet whose conduit extends down into the liquid in the vessel, a tube surrounding the first named tube and an air space between the same, an air exit passage E^7 inclined upward and outward, and in the outer tube a larger passage J^4 axially opposite the first named exit passage, and 115 an exit conduit from such vessel a screw-stem being present and adapted to control the said outlet E^7 of the first named tube substantially as and for the purposes specified. 120

6. In an inhalation apparatus, a vessel provided with an air inlet whose conduit extends down into the liquid to be nebulized, and provided with a second space J^2 formed by an outer wall, an exit through the wall 125 of the conduit and through this outer wall, both passages inclined upward and outward, and a valve inclined as shown and screwed through one wall of the conduit and seated at the beginning of the passage through this 130

wall, substantially as and for the purposes specified.

7. In an inhalation apparatus, a vessel provided with an air inlet whose conduit extends down into the liquid in the vessel, a tube surrounding the first named tube and an air space between the same, an air exit passage E^7 inclined upward and outward, and in the outer tube a larger passage J^4 , axially opposite the first named passage, and a valve E^8 , for closing the first named exit passage, and an exit conduit from such vessel, the outer surface of the tube E^4 being of a reduced diameter at its lower portion for enabling the greatest diameter of the tube J^2 to also be of a reduced diameter, substantially as and for the purposes specified.

8. In an inhalation apparatus, a vessel provided with an air-inlet whose conduit extends down into the liquid to be nebulized and provided with a second space J^2 formed by an outer tube, an exit through the wall of this conduit and through this outer wall both passages inclined upward and outward, and a valve controlling the exit passage through the inner tube, and inclined as shown and screwed through the walls of each tube, and supporting the outer tube, substantially as and for the purposes specified.

9. In an inhalation apparatus, a vessel, an inlet air tube E^4 , closed at bottom, and containing two or more inclined exit passages E^7 , and an outer tube J^3 having two or more passages J^4 respectively alining with said passage E^7 , and valves each having screw threaded shanks, respectively to control the exit passages E^7 , and screwed through the wall of tube E^4 and the wall of tube J^3 , and engaged screw threads in said walls, substantially as and for the purposes specified.

10. In an inhalation apparatus, a vessel for containing the liquid and the exit conduit tube F and the inlet conduit tube E, and the conduit extending from tube E, and passing around tube F, and connected with conduit extended down into the atomizing chamber, and the exit conduit from the vessel communicating with the tube F, all the conduits except tubes F and E the tube extending into the atomizing chamber and the valves being formed within the single piece of metal in which the tubes E and F are respectively inserted, as shown, a valve being present in the conduit between inlet tube E and the vessel, and a valve being present in the conduit F between the vessel and the said tube F, substantially as and for the purposes specified.

60 11. In an inhalation apparatus, a vessel for containing the liquid and the exit conduit F and the inlet conduit tube E, and the conduit extending from tube E and passing around tube F, and passing down and is connected with conduit extended down into the atomiz-

ing chamber, the conduit tube E and the portion of tubing around tube F being of large diameter and thereafter reduced in size, for a certain distance, and exit conduit from the vessel, and a valve for controlling the inlet and exit passages, all of the conduits except E, F and the one extending into the atomizing chamber, and the valve, being in one piece, substantially as and for the purposes specified.

75 12. In an inhalation apparatus, a vessel for containing the liquid, and an inlet conduit tube E, and the exit conduit from the vessel, and the valve having a shank inclined and provided with the two transverse passages F^7 and E^5 , each angulated relatively to the axis of the shank and to each other, the shank provided at its outside surface with the channel E^6 , and the tubular portion or extension F^2 , containing the passage, F^6 , and the air passage E^3 , the passage F^6 adapted to aline with the opening F^7 of the key-shank G, and the air passage E^3 adapted to aline with the passage E^5 of the key-shank G, and the channel or passage E^6 adapted to connect the passage F^6 with the air passage E^3 , according as the key-shank G of the valve is rotated, substantially as and for the purposes specified.

80 13. In an inhalation apparatus, a vessel for containing the liquid and the exit conduit tube F and the inlet tube E, and the conduit extending from tube E and passing around tube F, and passing down and connected with conduit extended down into the atomizing chamber, the conduit tube E and the portion of tubing around tube F being of large diameter and thereafter reduced in size, for a certain distance, and exit conduit from the vessel, and a valve for controlling the inlet and exit passages, all of the conduits except 90 E, F and the one extending into the vessel, and the valve, being in one piece, the shank being provided at points other than the terminals of passages F^7 and F^5 with a lengthwise passage E^6 , for enabling the inlet and exit tubes to be connected when all connection between the vessel and these tubes is closed, substantially as and for the purposes specified.

95 14. In an inhalation apparatus, a vessel for containing the liquid and the exit conduit tube F and the inlet tube E, and the conduit extending from tube E and passing around tube F, and passing down and connected with conduit extended down into the atomizing chamber, the conduit tube E and the portion of tubing around the tube F being of large diameter and thereafter reduced in size, for a certain distance, and exit conduit from the vessel, and a valve for controlling the inlet and exit passages, all of the conduits except E, F and the one extending into the vessel, and the valve, being in one piece, the shank being provided at points other than the terminals of passages F^7 and F^5 with a 100

- lengthwise passage E⁶, for enabling the inlet and exit tubes to be connected when all connection between the vessel and these tubes is closed, and index G³, and on the valve shank 5 a handle and three-pointed index, whose fingers are respectively marked to indicate the position of the valves relatively to the inlet and exit passages, substantially as and for the purposes specified.
- 10 15. In an inhalation apparatus, a vessel for containing the liquid and the exit conduit tube F and the inlet tube E, and the conduit extending from tube E and passing around tube F, and passing down and connected with conduit extended down into the atomizing chamber, the conduit tube E and the portion of tubing around tube F being of large diameter and thereafter reduced in size, for a certain distance, and exit conduit from the vessel, and a valve for controlling the inlet 20 and exit passages, all of the conduits except E, F and the one extending into the vessel, and the valve, being in one piece, the shank being provided at points other than the terminals of passages F⁷ and F⁵ with a lengthwise passage E⁶; for enabling the inlet and exit tubes to be connected when all connection between the vessel and these tubes is closed, and index G³, and on the valve shank, 25 a handle and three-pointed index whose fingers are respectively marked "On," "Off," "Air," substantially as and for the purposes specified.
